CHAISE LOUNGE

Ernest Dawson Race, Barnes, London, England, assignor to Ernest Race Limited, London, England, a company of Great Britain and Northern Ireland

Application February 16, 1954, Serial No. 29,052

Claims priority, application Great Britain January 6, 1954

Term of patent 7 years

(Cl. D15—11)

Fig. 2.

Fig. 1.

To all whom it may concern:

Be it known that I, Ernest Dawson Race, a subject of the Queen of Great Britain and Northern Ireland, residing at London, England, have invented a new, original, and ornamental Design for a Chaise Lounge, of which the following is a specification, reference being had to the accompanying drawings, forming part thereof.

Fig. 1 is a perspective view of a chaise lounge showing my new design.

Fig. 2 is a perspective view from the other side.

Fig. 3 is a front elevation.

I claim:

The ornamental design for a chaise lounge, as shown.
